US0D1027422S

(12) **United States Design Patent** (10) **Patent No.:** **US D1,027,422 S**
(45) **Date of Patent:** **** May 21, 2024**

(54) **KNIFE COVER**

(71) Applicant: **Yangjiang Lici Technology Co., Ltd.**,
Yangjiang (CN)

(72) Inventor: **Jibiao Feng**, Guangzhou (CN)

(73) Assignee: **Yangjiang Lici Technology Co., Ltd.**,
Yangjiang (CN)

(**) Term: **15 Years**

(21) Appl. No.: **29/835,165**

(22) Filed: **Apr. 15, 2022**

(51) LOC (14) Cl. **03-01**

(52) U.S. Cl.

USPC **D3/201**

(58) **Field of Classification Search**

USPC D3/201, 215, 220, 228; D7/649; 30/143,

30/151; 224/232, 242; D22/118

CPC B26B 29/025
